UNITED STATES PATENT OFFICE.

EMIL MOTTERT, OF HOYLETON, ILLINOIS.

SHOE LAST.

Application filed April 6, 1927. Serial No. 181,460.

This invention relates to the art of making shoes and has especial relation to lasts used when sewing the seams of shoe tips.

An object of the present invention is to provide a last for this purpose which may be readily inserted within a shoe and quickly and easily adjusted and held in adjusted position and readily and quickly removed from the shoe after use, novel means being provided for adjusting the length of the last and holding the same in adjusted position, the said means permitting of a rapid collapsing of the last prior to removal.

With the above and other objects in view, the invention further includes the following novel features and details of construction, to be hereinafter more fully described, illustrated in the accompanying drawings and pointed out in the appended claims.

20 In the drawings:

Figure 1 is a sectional view of a shoe with the invention in position for use.

Figure 2 is a plan view of the invention.

25 Figure 3 is an enlarged fragmentary section taken on the line 3—3 of Figure 2.

Figure 4 is a similar view with the parts in released position to permit of rapid adjustment.

30 Figure 5 is a view similar to Figure 3 with the parts in a different position.

Figure 6 is a section on the line 6—6 of Figure 3.

Figure 7 is a section on the line 7—7 of 35 Figure 5.

Figure 8 is a detail perspective view of the socketed member.

Figure 9 is a similar view of the releasing member.

40 Referring to the drawings in detail wherein like characters of reference denote corresponding parts, the last which constitutes the present invention is shown as comprising a toe section 10 and a heel section 11,

45 the said sections being adjustably connected by means of a bar 12.

The toe section 10 is designed to fit within the toe portion of a shoe 13 to facilitate sewing the shoe tip 14, the heel section 11 and the bar 12 acting to hold the toe section in place.

50 The heel section comprises a channeled member which includes a bottom 15 and side walls 16, the rear ends of the latter being connected by a curved end wall 17 which is designed to engage the inner heel portion

of the shoe. The bar 12 is provided in its opposite side edges with longitudinally disposed grooves 18 within which extend tongues 19, the latter projecting inwardly 60 from the side walls 16, so that a sliding engagement is provided between the bar and the heel section 11. The bar is further provided upon its upper face with teeth 20.

Pivottally mounted between the side walls 16 of the heel section 11 upon a pin 21 is a handle socket 22, shown in detail in Figure 8 of the drawings. This handle socket includes spaced plates 23 which are provided with openings 24 for the passage of the pin 70

21. The handle socket 22 is preferably formed from a single blank of material, the sides of which are connected by pins or rivets 25 which extend through ears 26. The plates 23 are also provided with registering 75

openings 27 for the reception of a pivot pin 28, the latter passing through the inner end of a power dog 29 which is adapted to engage the teeth 20. A spring 30 which has one of its ends bearing against the dog and its opposite end bearing within the handle 80

socket 22 serves to normally force the dog 29 downward. A suitable handle 31 is adapted to be placed within the member 22 and when the latter is rocked upon the pin 21, the bar 12 may be moved with respect to the heel section 11 through the medium of the dog 29, as will be readily understood.

In order to prevent retrograde movement 90 of the bar 12 there is provided a holding dog 32 whose inner end is mounted upon the pin 21. This dog is forced downward under the action of a spring 33 which is arranged in a manner similar to the spring 30.

Also pivottally mounted upon the pin 21 is a releasing member 34. This member is provided with teeth 35 and 36 which are designed to engage pins 37 and 38 carried respectively by the dogs 29 and 32. The releasing member 34 further includes a handle 39, by means of which it may be pivottally 95

moved so that the teeth will engage the pins as just mentioned and raise the dogs 29 and 32 out of the path of the teeth 20 and permit rapid relative adjustment between the toe and heel sections of the last.

The releasing member 34 is provided with a laterally offset lug 40 to which is attached one end of a spring 41. The opposite end of this spring is secured to one end of a spacing bracket 42 mounted between the side walls 16 of the heel section 11. The spring 100

110

41 serves to normally hold the releasing member in the position shown in Figures 3 and 5 of the drawings so as not to interfere with the pivotal movement of the dogs 29 and 32.

By raising the dogs 29 and 32 in the manner described, the last may be inserted within a shoe and the toe and heel sections given a rapid initial adjustment, final adjustment being effected through the operation of the handle 31. To remove the last, the releasing member 34 is operated to again raise the dogs 29 and 32 so that the toe and heel sections may be moved relatively inward and the last conveniently removed from the shoe.

The invention is susceptible of various changes in its form, proportions and minor details of construction and the right is herein reserved to make such changes as properly fall within the scope of the appended claims.

Having described the invention what is claimed is:—

1. A shoe last comprising a toe section and a heel section, a toothed bar having one end secured to one section, a sliding connection between the bar and the other section, a socketed handle member pivotally secured to one of the sections, a dog pivotally mounted within the lower portion of the handle member and extending therefrom to engage the toothed bar to move the latter and adjust the sections relatively, and a holding dog also pivotally mounted within the handle section.

2. A shoe last comprising a toe section and a heel section, a toothed bar having one end secured to one section, a sliding connection between the bar and the other section, a dog carried by one section for engagement with the toothed bar to adjust the sections relatively and hold them in adjusted position, means to operate the dog, and means mounted within the sections to move the dog to an inactive position.

3. A shoe last comprising a toe section and a heel section, a toothed bar having one end secured to one section, a sliding connection between the bar and the other section, a

socketed handle member pivotally secured to one of the sections, a dog pivotally mounted within the lower portion of the handle member and extending therefrom to engage the toothed bar to move the latter and adjust the sections relatively, a holding dog also pivotally mounted within the handle section, and means mounted within the sections to move the dogs out of the path of the bar.

4. A shoe last comprising a toe section and a heel section, a toothed bar having one end secured to one section, a sliding connection between the bar and the other section, pivotally movable means associated with one of the sections and with the slideable means to adjust the sections relatively and hold them in adjusted position, a pivotally mounted releasing member, and means carried by said member to release the section holding means.

5. A shoe last comprising a toe section and a heel section, a toothed bar having one end secured to one section, a sliding connection between the bar and the other section, a socketed handle member pivotally secured to one of the sections, a dog pivotally secured to the handle member and engaging the toothed bar to move the latter and adjust the sections relatively, and means normally disengaged from the dog and capable of being moved into engaging position to operate the dog and release the bar.

6. A shoe last comprising a toe section and a heel section, a toothed bar having one end secured to one section, a sliding connection between the bar and the other section, a socketed handle member pivotally secured to one of the sections, a dog pivotally mounted within the lower portion of the handle member and extending therefrom to engage the toothed bar to move the latter and adjust the sections relatively, and a pivotally mounted releasing member located adjacent to and movable independently of the handle member to actuate the dog and release the bar.

In testimony whereof I affix my signature.

EMIL MOTTERT.
